UNITED STATES PATENT OFFICE

JESSE G. BATES, OF CHICAGO, ILLINOIS

STAPLING DEVICE

Application filed September 20, 1928. Serial No. 307,198.

This invention relates to stapling devices of the type wherein a strip of staples is fed step-by-step to a plunger which severs the forward staple from the strip and drives it into the work operated upon.

The main objects of this invention are to provide a stapling device having improved means for supporting and guiding the strip of staples; to provide improved mechanism for feeding the staple strip step-by-step to the plunger; to provide a feeding mechanism of this kind which will secure the forward staple against tilting during its movement to the plunger; to provide improved means for securing the staples against backward movement in their guideway; to provide an improved form of gate for limiting the forward movement of the strip; to provide a gate of this kind which is retractable to permit the entire strip of staples to be readily withdrawn from the machine; and to provide a stapling device having an improved form and arrangement of parts whereby the last staple in a strip is automatically ejected, unused, from the machine after the preceding staple has been acted upon by the plunger.

An illustrative embodiment of this invention is shown in the accompanying drawings, wherein:

30 Figure 1 is a side elevation, partly in section, of a stapling device to which this invention is applied, part of a staple strip being also shown.

35 Fig. 2 is a front elevation of the same, part of the plunger handle being broken away.

Fig. 3 is a bottom plan of the same.

Fig. 4 is an enlarged sectional detail showing the position assumed by the last staple of a strip as it is ejected past the gate, the view being taken on the line 4-4 of Fig. 2.

Fig. 5 is a fragmentary section taken on the line 5-5 of Fig. 2.

Fig. 6 is a fragmentary perspective of the plunger.

45 Fig. 7 is an enlarged perspective of the feeding element.

Fig. 8 is an enlarged perspective of the supporting and guiding means for the strip of staples.

50 Fig. 9 is a sectional detail taken on the line

9-9 of Fig. 8 and showing the means for securing the staples against backward movement.

Fig. 10 is a fragmentary side elevation of the device showing the gate open and a strip 55 of staples partially withdrawn.

In the construction illustrated, the improved stapling device comprises a support 1, having a guideway 2 for supporting and guiding a strip of U-shaped staples 3, which are severed and driven into the work by a plunger 4, to which the strip is fed by an improved feeding mechanism 5.

The support 1 is preferably a metal casting comprising a base 6 and head 7 having an integral handle 8.

The improved guideway 2 includes a channel 9 in which is located a rail 10 for supporting and guiding the strip of staples. The channel 9 is formed in the base part 6 and is coextensive therewith. An inlet opening 11 at the rear end of the channel permits the insertion of the staple strip and an outlet opening 12 at the forward end of the channel permits the withdrawal of the strip if desired, 75 and also permits the ejection of the last staple as hereinafter described.

The guide-rail 10 is located in the forward part of the channel 9 and is rigidly secured to the base 6 by rivets 13 or other suitable fastening means.

In the form shown, the rail 10 includes a bar 14 on which is rigidly mounted a cutter plate 15. By making the bar 14 and plate 15 in two parts, it is not necessary to harden the entire rail. The plate 15 is made of hardened steel and the bar 14 may be a die casting.

The plate 15 supports the staple strip and, therefore, is slightly narrower than the staples so as to permit the strip to slide freely. The upper part of the bar 14 is reduced in cross section so as to provide passages 16 for the prongs of the staples. The rear end of the rail 10 is tapered, as shown at 17, to facilitate the insertion of the staples.

Formed on opposite sides of the bar 14, adjacent the forward end thereof, is a pair of recesses 18, through which dust or other foreign particles may be expelled from the guideway.

5 Mounted on the rail 10 adjacent the forward end thereof, is a detent mechanism arranged to secure the staples against backward movement. In the form shown, the detent mechanism includes a pair of detents 19, located on respectively opposite sides of the bar 14, and having their rear ends pivotally secured thereto by pins 20.

10 The detents are normally urged outwardly into engagement with the prongs of the staples 3 by a spring 21 which extends through a transversely disposed opening 22 formed in the bar 14. By engaging the prongs of the staples, the detents 19 positively 15 secure the staples against any backward tilting during the retraction of the feeding mechanism 5, as hereinafter described.

15 The plunger 4 is slidable in a guideway 23, formed in the head 7, and is provided with 20 a cutting edge 24 adapted to coact with the forward edge of the plate 15 for severing the foremost staple from the strip. The lower end of the plunger is adapted to drive the severed staple through a guideway 25 25 extending substantially normal to the guideway 2.

20 Mounted on the outer end of the plunger 4, is a knob 26 and, loosely embracing the plunger, is a cup shaped washer 27 which 30 bears against the head 7.

25 Bearing between the knob 26 and washer 27, is a spring 28, which normally retracts the plunger to its inoperative position, as shown in Fig. 1. The plunger is secured 35 against withdrawal from the head 7 by a pin 29 extending transversely through the head in position to engage a shoulder 30 formed on the plunger.

30 In the form shown, the improved feeding mechanism 5 comprises a pawl 31 located in the rear part of the guideway 23 and pivotally secured to the head 7 by a pin 32.

35 The lower end of the pawl 31 is formed so as to be adapted to straddle the guide-rail 45 10 and is provided with a pair of spaced fingers 33 adapted to engage the two prongs of a staple for feeding the strip forwardly in a step-by-step movement. By engaging the two prongs of the staple, the pawl 31 50 secures the staple against any tilting during the forward movement.

45 The pawl 31 is moved forwardly, for feeding the staples, under the action of a spring 34 which embraces the pin 32. One end of 55 the spring 34 engages the wall of the head 7 and the other end thereof bears against an inclined cam plate 35 formed on the pawl.

50 The backward stroke of the feed pawl 31 is positively limited by an adjustable screw 36 60 mounted in the head 7 and positioned to engage the cam plate 35.

65 The cam plate 35 is located in the path of the shoulder 30 so that upon the operative stroke of the plunger, the pawl 31 is retracted for engagement with another staple.

The forward movement of the strip of staples is limited by a gate 37, which comprises a resilient arm 38 pivotally secured to the head 7 by a pin 39. The free end of the arm 38 is bent to provide a shoulder 40, 70 which is adapted to be seated in one side of the outlet 12 for preventing the withdrawal of the strip. The shoulder 40 is provided with a projection 41 adapted to enter a recess 42 in the base 6 for securing the gate 75 against accidental withdrawal.

75 The arm 38 is slightly bent, as shown at 43, so that the free end thereof must be pressed toward the base 6 before the shoulder 40 can enter the opening 12.

80 The gate 37 obstructs one side of the outlet 12 and therefore makes it impossible to remove the strip of staples without retracting the gate, as illustrated in Fig. 10. However, when only one staple is left, it is ejected past 85 the gate in the manner indicated in Fig. 4.

85 In operation, a strip of staples is placed in the guideway 2 and moved forwardly until the foremost staple engages the shoulder 40 of the gate. By depressing the plunger 90 4, the foremost staple is severed from the strip and driven through the guideway 25 into the work operated upon. During the depression of the plunger, the shoulder 30 moves the feed pawl 31 rearwardly to permit 95 the fingers 33 to engage the prongs of another staple.

90 During the retraction of the feed pawl 31, the staples are secured against backward movement by the improved detents 19. Upon 100 the return stroke of the plunger, the pawl 31 is actuated by the spring 34 for feeding the staples one step forwardly.

105 The spring 34 is arranged so as to enable the pawl 31 to exert considerable pressure on the staple strip and, therefore, if the gate 37 were open during the forward movement of the pawl, the forward end of the staple strip would be projected through the outlet 12 beyond the guideway 25 by the catapulting 110 action of the pawl 31.

115 As long as the gate 37 is closed it is impossible for two connected staples to pass beyond the guideway 25 because, in order to pass the gate 37, it is necessary that the staple shift to a diagonal position, as shown in Fig. 4. The outlet opening 12 is not of sufficient width to permit two connected staples to turn diagonally therein and, therefore, when the gate 37 is closed the foremost staple of the 120 strip stops in alignment with the guideway 25.

125 After the next to the last staple is driven through the guideway 25, the feed pawl 31 ejects the last staple through the opening 12 in the manner illustrated in Fig. 4.

130 The last staple of the strip is always wasted in any type of stapling device but, with the devices heretofore in use, the last staple has merely fallen out of the same opening 130

through which the preceding staples were driven. With prior devices, the last staple frequency became caught in the outlet and clogged the machine.

5. Clogging of the machine is avoided in devices embodying this invention because the last staple of each strip is automatically ejected through the outlet 12.

Although but one specific embodiment of 10 this invention has been herein shown and described, it will be understood that numerous details of the construction shown may be altered or omitted without departing from the spirit of this invention as defined by the 15 following claims.

I claim:

1. A stapling device comprising a support, a guideway on said support for a strip of staples, said guideway having an outlet at 20 one end in prolongation thereof, means for severing the foremost staple from the strip, and mechanism for feeding the strip along said guideway to said severing means, said feeding mechanism being adapted to throw 25 the last staple of the strip to eject same through said outlet after the preceding staple has been severed.

2. A stapling device comprising a support, a guideway on said support for a strip 30 of staples, said guideway being open at one end for the insertion of the strip, means for severing the foremost staple from the strip, and mechanism for feeding the strip to said severing means, said guideway having an outlet 35 opening at its opposite end in prolongation therof, said feeding mechanism being adapted to throw the last staple of the strip to eject same through said outlet after the preceding staple has been severed.

40. 3. A stapling device comprising a support, a guideway on said support for a strip of staples, said guideway having an outlet at one end in prolongation thereof, means for severing the foremost staple from the strip, 45 mechanism for feeding the strip along said guideway to said severing means, and a stop in said outlet for limiting the forward movement of the strip, said feeding mechanism being adapted to throw the last staple of the 50 strip to eject same through said outlet.

4. A stapling device comprising a support, a guideway on said support for a strip of staples, said guideway having an outlet opening at its forward end in prolongation thereof, means for severing the foremost staple from the strip and driving it in a direction substantially normal to the strip, mechanism for feeding the strip along said guideway to said severing means, and a gate located in 55 said outlet for limiting the forward movement of said strip, said gate being retractable to permit the strip to be withdrawn through said outlet, said feeding mechanism being adapted to throw the last staple of the strip 60 to eject same through said outlet.

5. A stapling device comprising a support, a guideway on said support for a strip of staples, said guideway having an outlet opening at its forward end in prolongation thereof, means for severing the foremost staple from the strip and driving it in a direction substantially normal to the strip, mechanism for feeding the strip along said guideway to said severing means, and a gate located in said outlet at one side thereof for limiting the forward movement of said strip, the opposite side of said outlet being unobstructed to permit the ejection therethrough of the last staple of the strip.

Signed at Chicago this 15th day of September, 1928.
